Sigmund Herzog

UNITED STATES PATENT OFFICE

BENJAMIN HIRSCHHORN, OF NEW YORK, N. Y., ASSIGNOR TO MILLIE PATENT HOLDING CO., INC., OF NEW YORK, N. Y., A CORPORATION OF NEW YORK

TEA CARTRIDGE

Application filed April 18, 1929. Serial No. 356,055.

The present invention relates to improvements in tea cartridges for percolating or extracting the flavor from tea-leaves or coffee. The invention pertains more particularly to that type of tea-cartridges which is described in U. S. Letters Patent #1,310,796, granted to me on July 22, 1919.

In the Letters Patent mentioned, a device for extracting essence from tea-leaves or coffee is described, comprising a bag of textile fabric which contains a quantity of tea-leaves or coffee just sufficient for a single brewing. The mouth of the bag is drawn into folds and closed by a metal strip, bent into the shape of a ring, engaging and compressing said folds and thereby closing the mouth of said bag; said strip attaching at the same time to said bag a suspending string, to the free end of which is secured in any suitable manner a tag or handle of cardboard or the like, on which may be displayed, by printing or otherwise, advertising matter and identification marks of the tea contained in the cartridge. When these articles of commerce are put up in packages for retail sale, they are usually thrown indiscriminately into a box or bag. The result is that the suspending strings become tangled in a confused and not readily separable mass so that, when these cartridges are to be put to use, it is often necessary to cut the suspending strings, which fact renders the cartridges practically unfit for use. At least it impairs the use thereof.

The main object of the present invention is to provide a cartridge of the character mentioned which is so constructed that its suspending string is less apt to intertwine with others, and if tangled with others can be readily separated therefrom.

Another object of the invention is to provide a tea-cartridge of the character described which is simple in construction, efficient in operation and capable of manufacture on a commercial scale, or in other words one which is not so difficult to produce as to be beyond the reasonable cost of such a contrivance.

With these and other objects in view, which will more fully appear as the nature of the invention is better understood, the same

consists in the combination, arrangement and construction of parts hereinafter described, pointed out in the appended claim and illustrated in the accompanying drawings, it being understood that many changes 55 may be made in the size and proportion of the several parts and details of construction within the scope of the appended claim, without departing from the spirit or sacrificing any of the advantages of the invention. 60

In practice it has been found that the tangling of the suspending strings of the tea-cartridges is brought about by the fact that the tags on the unattached ends of the strings cause an intertwining of the said strings. It 65 has also been found that, if the tags overlie the bags or containers of the cartridges, the strings do not become tangled.

The invention herein described consists in slidably mounting the suspending strings on the cartridges so that the strings may be drawn through the bag-closing rings as far as the tags permit, whereby the said tags overlie the bags or containers and the other ends of the strings are free. The last-mentioned ends of the strings are provided with stops, to prevent disengagement of the strings from the bag-closing rings when the tags are brought into the positions which they occupy when the cartridges are being 70 used for making an infusion. 75

A few of the many possible embodiments of the invention are illustrated in the accompanying drawings, in which:—

Figure 1 is an elevation of a tea-cartridge 85 constructed in accordance with the present invention, the elements being in the positions ready for use; Fig. 2 is a similar elevation of the said bag with the handle or tag in a position in which it is prevented from intertwining with other strings; Fig. 3 is an elevation on a larger scale, of the attached portion of a suspending string and the stop thereon; Fig. 4 is a section taken on line 4—4 of Fig. 3, on a still larger scale; Fig. 5 is 90 an elevation of a modified tea-cartridge; Fig. 6 is an elevation, on a larger scale, of the attached end of the string and the stop of the cartridge shown in Fig. 5; Fig. 7 is a similar elevation, on an enlarged scale, of a 95 100

string end and a modified stop thereon; and Fig. 8 is a plan view of the blank of which the stop shown in Fig. 7 of the drawings is formed.

Referring now first to Figs. 1 to 4, inclusive, of the drawings, the numeral 10 indicates a bag of open mesh textile fabric, for instance cotton. This bag is of a size to contain just sufficient tea-leaves or coffee for a single brewing. The mouth of the bag is closed by drawing or gathering the same into folds to form a neck, and applying thereto a metal strip 11, bent into ring-shape, whereby the mouth of said bag is closed. Prior to applying the strip 11, there is placed against the folds of the bag one end of a suspending string 12, as shown in Fig. 1 of the drawings, so that the metal strip not only closes the mouth of the said bag but at the same time attaches the said string thereto. To the free end of the string is secured in any suitable manner a tag or handle 13 of cardboard or the like. The closing strip 11 is shaped to assume the form of a ring having a size to securely close the bag mouth but permitting sliding of the suspending string through the ring from the attached end of the said string to the tag on the free end thereof. Adjacent the attached end of the string and above the closing strip 11 is provided on the string a stop 14, which may be of any suitable construction. In the embodiment of the invention shown in Figs. 1 to 4, inclusive, it comprises an annulus 15 into which the string end is inserted, said annulus being then deformed, whereby it is firmly fixed to the string.

When the cartridge issues from the bag-making machine, the elements are in the positions shown in Fig. 1 of the drawings, in which the stop 14 is disposed above and close to the closing strip 11 and prevents disengagement of the string 12 from the bag, and the tag 13 is adapted to serve as a handle. For packing and shipping purposes the cartridge is prepared in the following manner: The operator takes hold of the stop 14 and draws the suspending string through the closing ring as far as the tag or handle permits, the elements being then in the positions shown in Fig. 2 of the drawings. When so prepared, the tags may be thrown indiscriminately into a box or like container and the suspending strings will not become tangled. To prepare a bag for use, the user takes hold of the tag or handle thereon and draws the string through the closing ring as far as the stop 14 on the string permits (Fig. 1).

A modification of the invention is illustrated in Figs. 5 and 6 of the drawings, which differs from the one above described in that the stop is in the form of a knot 16, tied on the initially attached end of the suspending string. Otherwise the construction and operation of the elements are the same as of

those described in connection with Figs. 1 to 4, inclusive, of the drawings.

A further modification of the stop is illustrated in Figs. 7 and 8 of the drawings. In this instance, the stop consists of a metal clip 17, applied to the initially attached end of the string. This clip is initially in the form of a flat strip of relatively short length, as shown in Fig. 8 of the drawings. The ends 18 of the said strip are pointed or triangular. In applying the clip to the string, the end of the latter is placed upon the flat strip and the triangular ends bent over and flattened against the string, whereby the clip is clamped to said string. The operation of this device is obvious from the foregoing.

It is to be noted that, while herein stops of specific configurations have been described, any others may be used without departing from the invention, which consists mainly in so mounting the suspending string on the cartridge that it may be drawn through the closing ring thereof for the purpose mentioned.

What I claim is:—

A device for extracting essence from tea-leaves or coffee, comprising a bag having its mouth drawn into folds, a metal strip engaging and compressing said folds for closing the mouth of said bag, a suspending string extended through said metal strip, a handle attached to one end of said string, and a stop on the other end of said string, said string being adapted to be drawn through said metal strip in either direction so that either said stop or said handle is adapted to be brought adjacent said metal strip.

Signed at New York city, in the county of New York, and State of New York, this 11th day of April, A. D. 1929.
